[57] CLAIM

The ornamental design for a roof top for bay windows, as shown and described.

DESCRIPTION

FIG. 1 is a front perspective view of the roof top for bay windows of the present invention;

FIG. 2 is a rear perspective view thereof;

FIG. 3 is a top plan view thereof;

FIG. 4 is a bottom plan view thereof;

FIG. 5 is a front elevational view thereof;

FIG. 6 is a rear elevational view thereof; and,

FIG. 7 is a left side elevational view thereof, the right side elevational view being a mirror image.

The broken lines showing the bay window is for illustrative purposes only and forms no part of the claimed design.
